STADIUM SEAT

Florence Du Priest, Waco, Tex.

Application September 24, 1953, Serial No. 382,063

3 Claims. (Cl. 155—133)

This invention relates to a stadium seat.

It is an object of this invention to provide a foldable and portable stadium seat to be easily carried by a user when and where desired.

It is an important object of this invention to provide a foldable and portable stadium seat for releasable hooked connection to a stadium seat and releasable connection of a bag to the stadium seat, the bag being foldable between the seat and the back of the foldable seat in the folded condition thereof.

It is a further object of this invention to provide a lightweight and foldable stadium seat of the kind to be particularly described hereinafter which may be easily carried about by the user and constructed at an economical cost by manufacturers to be distributed at an attractive price to the buyer.

Other and further objects and advantages of the invention will be hereinafter described and the novel features thereof defined in the appended claims.

In the drawings:

Fig. 1 is a perspective view of a foldable stadium seat constructed according to an embodiment of this invention, the stadium seat being in its unfolded and open condition.

Fig. 2 is a side elevation, partly in section, of the folding seat shown in Fig. 1.

Fig. 3 is a top plan view of the stadium seat in its folded position.

Fig. 4 is a transverse section taken on the line 4—4 of Fig. 3.

Fig. 5 is a fragmentary, enlarged, detailed section taken on the line 5—5 of Fig. 1.

Fig. 6 is a fragmentary enlarged detailed section taken on the line 6—6 of Fig. 3.

Fig. 7 is a fragmentary, enlarged rear elevation of the seat attaching hook of this invention.

Fig. 8 is a fragmentary enlarged side elevation of the seat attaching hook.

Referring to the drawings the numeral 10 designates generally a stadium seat constructed according to an embodiment of this invention. The stadium seat 10 is adapted to be seated onto a conventional stadium seat S and the stadium seat 10 may be carried about by a person using the seat and desiring a covering for the stadium seat S at any particular position where the owner of the stadium seat 10 desires. The stadium seat 10 is formed with a foot bag 11 connected thereto to be wrapped about the feet of the user of the seat 10 under certain weather conditions where it is particularly desirable to have the feet of the user covered.

The stadium seat 10 is formed with a seat frame 12 and a back frame 13 pivotally connected thereto so that the back frame 13 may be extended upwardly from the seat frame 12 when the seat 10 is to be used. A cover 14 is suitably secured to both of the frames 12 and 13 and will provide a hinged connection at the juncture of the frames 12 and 13 so that the back frame 13 may be moved upwardly from the seat frame 12 to

2

the unfolded position as clearly shown in Fig. 1 of the drawings. A flexible cord 15 is secured at one end to the seat frame 12 and at the other end to the back frame 13. The ends of the cord or brace 13 are suitably secured to the frames 12 and 13 intermediate the length thereof.

10 A handle 16 is secured to one of the frame members, as the back frame member 12, intermediate the length thereof so that when the frames 12 and 13 are folded together the entire seat 10 may be carried about from one place to another.

15 A length of zipper 17 is secured to the opposite side edges of the cover 14 and extends along the length of the back and seat of the portable seat 10. A slider 18 is slidable along the length of each of the zippers 17 and may be moved with the zipper handle 19. Each of the zippers 17 is provided with zipper teeth 18 secured on a zipper tape so that the slider 17, upon its movement along the length of each of the zippers will effect the inter-engagement of the zipper teeth on the co-related zippers of the seat and back of the stadium seat 10.

20 In order to secure the stadium seat 10 to a rigid stadium seat S, a hinge is provided for attachment to the seat frame 12 and to the rigid seat S. The hinge for connection of the stadium seat 10 to the rigid stadium seat S, comprises a horizontal hinge barrel 23 longitudinally of the seat frame 12 adjacent the opposite sides of and at the forward edge of the seat frame and the hinge arm 28 is rotatable about the hinge about a horizontal axis. A bolt 26 is secured for rotary movement to the hinge arm or flap 28 for rotatable movement from a folded position underlying the seat of the stadium seat 10 to a vertically extending position hooked over one edge of the stadium seat S. A hook 25 is fixed to or formed on the other end of the bolt 26 and will underlie the bottom portion of the stationary stadium seat S, as clearly shown in Fig. 5 of the drawings.

25 The hinge for the hook 25 comprises one hinge leaf 25' extending horizontally of the seat of the stadium seat 10 and the second leaf or flap 28 which is normally extended in a vertical position depending from the hinge leaf 27 as clearly shown in Figs. 2 and 5 of the drawings.

30 The flap 28, or hinge leaf will depend from the hinge and lie outwardly of the hook 25. The bolt 26 is rotatable in relation to the hinge arm 28 and is biased by a spring 24 in a direction to hook the hook under the seat S. The arm 28 is biased in its rotation in the spring by resilient spring means in such a manner that the bolt 26 and the flap 28 are spring pressed in their rotation about the spring 24' to a position parallel to the hinge leaf 27 when the seat 10 is removed from the stadium seat S.

35 When the stadium seat 10 is hookingly engaged on the seat S, the foot bag 11 may be secured to the forward edge of the lower horizontal seat of the seat 10 by suitable snap fasteners. Snap fasteners 29 are secured to one edge of the foot bag 11 and co-related snap fasteners 30 are fixedly secured to the forward edge of the seat frame 12 for detachably securing the foot bag 11 to the seat 10 when and as desired.

40 In the normal use and operation of the stadium seat 10, the back 13 will be initially extended from the seat 12 and the foot bag 11 secured thereto. The rear wall 20 of the foot bag 11 will carry the snaps 29 for engagement with the snaps 30 which are fixed on the seat. When the seat 10 is to be folded in its closed position, the foot bag 11 is initially disengaged from the seat frame 12 and placed to be between the seat and the back of the seat as the back of the seat is folded into overlying posi-

tion with the seat of the seat 10. The flaps 28 may then be hinged onto the seat portion of the seat 10 and the zippers moved to closed position so that the closed foldable seat 10 may be carried about by the handle 16 where and as desired.

While the specific details of one embodiment of this invention have been herein shown and described, the invention is not confined thereto as changes and alterations may be made without departing from the spirit and scope thereof as defined in the appended claims.

I claim:

1. A portable stadium seat comprising a seat frame, a back frame, a flexible cover secured to said back frame and seat frame, a hook hinged on said seat frame for engagement with a rigid seat of a stadium and movable from a position overlying said cover on said seat frame to a position for hooking engagement with the rigid stadium seat, a flexible bag, inter-engaging fastening means on said bag and said cover of said seat frame detachably securing said bag to said portable seat, an elongated flexible brace connected at one end to said back frame and connected at the other end to said seat frame, and a handle secured to said back frame.

2. A portable stadium seat of the kind described comprising a portable seat for overlying engagement on a rigid stadium seat, a seat back hinged on an edge of said portable seat, a flexible brace connected at one end to said portable seat and at the other end to said seat back, a hook hinged on said portable seat for movement from a position overlying said portable seat to a position for hooking engagement with the stadium seat, resilient means engaging said hook and said portable seat urging said hook to a position overlying said portable seat, a bag and

inter-engaging fastening means carried by said bag and said portable seat for detachably securing said bag to said portable seat.

3. A portable folding seat of the kind described comprising a seat, a seat back hinged on said seat for movement from a folded position overlying said seat to an extended position extending outwardly from said seat, a flexible brace connected at one end to said seat and at the other end of said back for limiting the movement of said back from said seat in the extended position, a foot bag, inter-engaging fastening means on an edge of said seat to detachably secure said foot bag to said seat, said foot bag being disposable between said seat and said back in the folded position thereof and depending from said seat in the extended position, hooks hingedly supported on said seat for hinged movement from a folded position overlying said seat to an extended position extending from said seat, resilient means between said hooks and said seat urging said hooks to the folded position overlying said seat, inter-engaging fastening means including a slider carried by said seat and said back for securing said seat to said back in folded position, and a handle on said back for carrying said portable folding seat in folded position.
